UNITED STATES PATENT OFFICE.

ARTHUR A. MIDDLETON, OF CANEY, KANSAS.

DISPLAY-FRONT FOR DRAWERS, &c.

SPECIFICATION forming part of Letters Patent No. 727,663, dated May 12, 1903.

Application filed February 3, 1903. Serial No. 141,716. (No model.)

To all whom it may concern:

Be it known that I, ARTHUR A. MIDDLETON, a citizen of the United States, residing at Caney, in the county of Montgomery and State 5 of Kansas, have invented certain new and useful Improvements in Display-Fronts for Drawers, &c.; and I do hereby declare the following to be a full, clear, and exact description of the invention, such as will enable others skilled in the art to which it appertains to make and use the same.

This invention relates to new and useful improvements in display-boxes for drawers and drawer-fronts and means for securing the drawer and releasing the same.

The invention consists, further, in various details of construction and combinations and arrangements of parts, which will be herein-after fully described and then specifically defined in the appended claims.

My invention is clearly illustrated in the accompanying drawings, which, with the letters of reference marked thereon, form a part of this application, and in which drawings similar letters of reference indicate like parts in the several views, in which—

Figure 1 is a front elevation showing my display-front as secured to a drawer-front. Fig. 2 is a side elevation showing the side of the drawer-front open and the display-front turned down with the drawer. Fig. 3 is a sectional view on line 3-3 of Fig. 2, and Fig. 4 is a perspective view showing the attaching device carried by the drawer-front.

Reference now being had to the details of the drawings by letter, A designates a cabinet which may contain drawers of the ordinary construction or slides upon which drawer-fronts are secured, it being my purpose to apply my improved metallic display-receptacle to various forms of drawer-fronts, fronts for shelving, &c.

B designates the front, pivotally mounted upon slides C, which have elongated slots C', that are adapted to slide between the opposite flanged edges of the strips D, which are fastened on the inner walls of the casing of the cabinet. Said slides C are pivoted at C² on the pins C³, carried at the lower ends of the shelf or drawer-front A. Hinged to the drawer-front B is a metallic framed display-box E, having glass faces, and a pin (shown

clearly in Fig. 3 of the drawings) has an eye e thereon, which pin is carried by the edge of the display-box and extends through an aperture e' in the drawer-front and is adapted to be engaged by means of a hook e², which is mounted upon the inner face of the drawer-front, whereby the display-box may be locked against the outer face of the drawer.

Pivotedly mounted in a recess in the under edge of the drawer-front is an angle-lever F, to one end of which is pivoted a link G, which in turn is pivoted at its lower end to a lever H, pivotally mounted upon a pin I. The free end of said lever H has an angled projection I', adapted to engage in a recess behind a plate K, projecting over a portion of said recess and fastened to the inner wall of the cabinet, as shown in the sectional view 70 of the drawings. An operating-lever N is pivoted to said angle-lever F and is in convenient reach to be operated for throwing the angle-lever F from the pivot accordingly as it is desired to throw the free end of the locking-lever behind or free from the plate over the recess in the wall of the cabinet.

While I have shown my display-box as applied to the drawer-front and also to a pivoted front mounted upon slides over a shelving, it will be understood that the metallic display-box may be applied to various other articles in which it may be desired to form a front to disclose the contents of the box or other receptacle to which it is attached, and I may make various alterations in the detailed construction of the apparatus without departing from the spirit of my invention.

Having thus fully described my invention, what I claim as new, and desire to secure by Letters Patent, is—

1. A display-box for drawer-fronts, comprising a metallic framed receptacle, with transparent faces, hinged to the drawer-front, an eye on the free edge of the display-box, means for holding the same locked to the drawer-front, and locking means for holding the drawer-front to the cabinet, as set forth.

2. In combination with a cabinet, slides mounted within the same, a pivoted drawer-front mounted on said slides, a display-box hinged to said front, and means for locking the display-box to said front, as set forth.

3. In combination with a cabinet, slides

mounted therein, a pivoted drawer-front mounted upon said slides, a display receptacle or box hinged to said front, an angle-lever pivoted in the recessed portion of the pivoted front, a locking-lever, link connections between the same and said angle-lever, and a rod pivoted to the angle-lever, as set forth.

In testimony whereof I affix my signature in presence of two witnesses.

ARTHUR A. MIDDLETON.
